[57] CLAIM

The ornamental design for a bite-wing dental x-ray film holder, as shown and described.

DESCRIPTION

FIG. 1 is a front view of a bite-wing dental x-ray film holder;

FIG. 2 is a left end elevation thereof;

FIG. 3 is a right end elevation thereof;

FIG. 4 is a top plan view thereof, the opposite being a mirror image of the top;

FIG. 5 is a cross-section taken on line 5—5 of FIG. 4; and

FIG. 6 is a top perspective view.

The broken lines representing the X-ray film is shown for illustrative purposes only.
